BAG GRAB

William G. Wehr, East Cleveland, Ohio, assignor
to The Cleveland Crane & Engineering Com-
pany, Wickliffe, Ohio, a corporation of Ohio

Application December 24, 1937, Serial No. 181,663

3 Claims. (Cl. 294—67)

The present invention relates to material handling and more particularly to the handling of heavy bags of material.

Heretofore in the art various types of grabs, slings, etc., have been employed in handling heavy bags of material, but these prior art methods have been unsatisfactory and expensive, and the principal object of the present invention is the provision of a novel method and novel equipment for handling heavy bags of material, particularly fine material such as sugar, whereby the handling of such material will be greatly facilitated and the cost thereof greatly reduced.

Another object of the present invention is the provision of a novel grab for handling heavy bags of material which can be easily manipulated to engage and disengage the load, and which will be reliable and efficient in operation.

Another object of the present invention is the provision of a novel grab for handling heavy bags of material which grab comprises a plurality of tines that can be readily inserted underneath a bag or bags of material and engage underneath thereof.

Another object of the present invention is the provision of a novel carrier for an overhead tramrail system especially adapted for the handling of heavy bags of material, so constructed and arranged that it can be readily operated or manipulated to pick up the load and discharge the same at a desired point with little if any manual handling.

Another object of the present invention is the provision of a novel carrier for an overhead tramrail system, said carrier being especially adapted for handling heavy bags of material and comprising a grab including a plurality of tines adapted to be inserted underneath the edges of a bag or bags of material, and means for manipulating the grab.

The present invention resides in certain details of construction and combinations and arrangements of parts, and further objects and advantages thereof will be apparent to those skilled in the art to which the invention relates from the following description of the preferred embodiments thereof described with reference to the accompanying drawings, forming a part of this specification, wherein similar reference characters designate the corresponding parts throughout the several views, and in which:

Fig. 1 is a side elevation of a carrier embodying the present invention supported on an overhead monorail system, only a part of the latter being shown;

Fig. 2 is a perspective view of the bag grab shown in Fig. 1 lifting a load of material in bag form;

Fig. 3 is an enlarged side elevation of the bag grab shown in the preceding figures;

Fig. 4 is a plan view of the bag grab shown in the preceding figures;

Fig. 5 is a rear elevation of the bag grab shown in the preceding figures;

Fig. 6 is a front elevation of the bag grab shown in the preceding figures;

Fig. 7 is an enlarged side elevation of the forward end of one of the tines of the bag grab shown in the preceding figures;

Fig. 8 is an enlarged plan of the tine shown in Fig. 7;

Figs. 9 to 12, inclusive, are sections taken on the lines 9—9, 10—10, 11—11, and 12—12, respectively, of Figs. 7 and 8;

Fig. 13 is a perspective view of the bag grab shown in the preceding figures being inserted underneath a load of material in bag form held in a loading skid;

Fig. 14 is a perspective view of a bag grab similar to that shown in the preceding figures, but of modified construction;

Fig. 15 is a section approximately on the line 15—15 of Fig. 14;

Fig. 16 is a side elevation of a bag grab of still further modified construction; and

Fig. 17 is a plan view of the bag grab shown in Fig. 16.

While the present invention is susceptible of various modifications and alternative constructions, it is herein illustrated and described as embodied in or applied to a carrier for an overhead tramrail system, especially designed for the handling of one hundred pound bags of sugar. However, it is to be understood that the invention is equally applicable to the handling of heavy bags of other material and may be used with material handling equipment other than an overhead tramrail system, various types of cranes, etc. The overhead tramrail system in which the preferred embodiment of the invention is incorporated is for the most part commercially known in the art and only those parts thereof which are necessary to a complete understanding of the present invention will be herein illustrated and described in detail.

Briefly stated, the method of handling heavy bags of material contemplated in the present invention comprises placing the bags of material in predetermined arrangement, or having the same placed in said arrangement, inserting the

tines of a grab of specific character forming a part of a suitable hoist mechanism underneath the bag or bags, and subsequently lifting the load by means of the grab and transporting it to the desired location.

As previously stated, the invention is particularly applicable to an overhead tramrail system and is herein shown and described as embodied in such a system.

Referring to the drawings, the reference character A designates a commercially known electrically propelled open-cab type of tandem carrier adapted to be traveled along the overhead monorail 10 of the electrified overhead tramrail system, under the control of an operator seated in the cab. The carrier A apart from the grab proper which is designated generally by the reference character B is commercially known in the art and will not be described in detail. Suffice it to say that the carrier A consists of two electrically propelled carriers 11 and 12 connected in tandem and provided with independent electric hoists 13 and 14. The traveling and hoisting mechanisms are under the control of an operator in the cab 15.

The bag grab proper, which is more or less U-shaped, is made up of structural shapes or members welded together and comprising a plurality of horizontal tines 20 connected to the lower ends of vertical T-beams 21 and to a horizontal cross member 22 comprising angle irons 23 and 24 all welded together in a suitable manner. The upper ends of the T-beams 21 are welded to a horizontal cross member 26 comprising angle irons 27 and 28, which in turn are welded to longitudinally extending spaced channel members 30 and 31 forming the upper leg of the U-shaped grab. The ends of the members 30 and 31 are connected together by plates 32 and 33 welded thereto and the whole assembly is connected to the blocks 16 and 17 and of hoists 13 and 14 through the medium of pins 34 and 35 positioned in aligned apertures adjacent the ends of the channel members 30 and 31. The upper part of the grab is braced by channel members 37 and 38 welded to the members 30 and 31 and to the free ends of the upper horizontal member 26 and by plates 39 and 40 connected to the channel members 37 and 38 intermediate the ends thereof and to the upper cross member 26. A brace 41 is interposed between the members 30 and 31 intermediate the cross member 26 and the end pin 34.

The tines 20 are of the construction shown in Figs. 7 to 12 inclusive and are made up of curved plates 45 and 46 welded together and to a flat horizontal plate 47. The forward end of each tine tapers down as indicated in the above mentioned figures. The radius of curvature of the curved plates 45 and 46 is about equal to the height of the tine except at the point where the end of the tine tapers down. There the radius of curvature increases gradually to approximate infinity at the end. In addition to tapering off towards the free ends, as viewed in elevation, the ends of the tines are rounded as at 48, as viewed in plan. This is clearly shown in Fig. 8. Triangularly shaped plates 49 welded to the upper edge of the tines and to the vertical T-beams 21 strengthen the rear ends of the tines against bending under load. The outside tines which are subjected to horizontal stress in only one direction may be braced along their outside edges as by plates 50 welded thereto and to the ends of the lower cross member 22 which, as shown,

project slightly beyond the outside tines for this purpose. The outside curved plates of the end tines are preferably omitted and plain plates substituted therefor, as shown in Figs. 14 and 15, but for the purpose of simplicity all the tines of the grab are shown uniform in Figs. 1 to 13 inclusive.

The tines are adapted to be projected underneath a load of material in bag form, by inserting the same into the interstices between the bags, and the cross section of the tines preferably is such that they substantially fill these interstices, thus preventing the material in the load from shifting and affording a substantial area of contact between the tines and the sides of the bags. The manner in which the load is lifted is clearly shown in Fig. 2. From this figure it will also be readily apparent that the spacing of the tines, that is, the distance between adjacent tines, is a function of the size of the bags being handled. Preferably, the width of the tines is such that about twenty to forty per cent of the projected area of the bag is supported. The material to be handled, preferably, is placed or piled in a predetermined manner, that is, in such a manner that the bags which engage the tines lie lengthwise thereon; otherwise, the tines cannot be inserted or withdrawn easily, if at all. The arrangement of the bags making up the load, other than the bottom row thereof, is immaterial. In the event that successive loads are placed one above the other, as is usually the case, it is desirable, although not necessary, to have the bags of the top row placed parallel to those of the bottom row, and successive loads should be placed with adjacent bags in vertical alignment, thus making it easier to insert the tines when it is desired to move the material at some subsequent time.

The arrangement of the bags in the desired manner does not present any problem whatsoever except when the material is being handled for the first time, in which event it may be expeditious to use a suitable form or skid. Such a skid is shown in Fig. 13 and consists of a box-like structure C, open at the front and top, adapted to hold one load of material. The boards or planks 52, which form the bottom of the skid, run crosswise and are spaced apart to provide adequate room for the entrance of the tines of the grab. It will be readily apparent that any type of suitable skid, other than that shown, may be employed. The fact that the grab proper is supported at opposite ends, by individually operable hoists, provides adequate control thereover and allows the operator of the carrier to manipulate the grab to engage and disengage a load, without the assistance of anyone else.

The grab shown in Figs. 14 and 15 is similar to that shown in the preceding figures, except that it is built up, for the most part, of tubular members welded together. The tines 55, which are similar in construction to the tines 20, except the outside or end tines which are varied in a manner previously referred to, are welded to a cross member comprising a plate 57 and an angle iron 58 and to the vertical tubular members 59. The upper ends of the vertical tubular members 59 curve forward where they are connected to a tubular cross member 60, directly above the center of gravity of the grab. The grab is adapted to be connected to suitable hoist mechanism, such as a carrier comprising only one hoist, in any convenient manner as by the chains 61.

A grab especially adapted for handling a single bag of material is shown in Figs. 16 and 17. As shown in these figures, the grab comprises two tines 63, similar in construction to the tines 28, welded to a cross member comprising a plate 64 and an angle iron 65 and to vertical tubular members 66 and 67, the upper ends of which are bent forward and connected together. Means in the form of a ring 68, connected to the members 66 and 67 and located above the center of gravity of the grab, is provided for attaching the hoist mechanism. The grab shown in Figs. 16 and 17, like the grab shown in the preceding two figures, is adapted to be connected to a single hoist.

It is thought that the operation of the device will be apparent to those skilled in the art to which it relates. From the foregoing description of the preferred embodiments of the invention, it will be apparent that the objects heretofore enumerated and others have been accomplished and that the present invention provides an improved method and novel equipment for handling material in bag form. While the preferred embodiments of the invention have been described in considerable detail, it will be readily apparent that the invention may be otherwise embodied. The present invention is not limited to the particular construction shown and described and it is the intention to cover hereby all adaptations, modifications, and variations thereof coming within the practice of those skilled in the art to which it relates, and within the spirit and scope of the appended claims.

Having thus described my invention, I claim:

1. In a grab of the character referred to adapted to be connected to a mechanical hoist and handle large heavy bags of material, the

combination of a supporting member, a plurality of substantially horizontally extending parallel tines connected to said supporting member and adapted to be inserted lengthwise underneath opposite sides of a substantially horizontally positioned large heavy bag of material and lift the same, said tines having bag-engaging sides diverging towards the bottom.

2. In a grab of the character referred to adapted to be connected to a mechanical hoist and handle large heavy bags of material, the combination of a supporting member, a plurality of substantially horizontally extending parallel tines connected to said supporting member and adapted to be inserted lengthwise into the apertures between adjacent large heavy bags of material arranged side by side in a substantially horizontal plane and engage underneath opposite sides of a bag and lift the same, said tines being generally triangular shaped transversely and having bag-engaging sides diverging toward the bottom.

3. In a grab of the character referred to adapted to be connected to a mechanical hoist and handle large heavy bags of material, the combination of a supporting member, a plurality of substantially horizontally extending parallel tines connected to said supporting member and adapted to be inserted lengthwise into the apertures between adjacent large heavy bags of material arranged side by side in a substantially horizontal plane and engaging underneath opposite sides of a bag and lift the same, said tines being generally triangular shaped transversely and having arcuate bag-engaging sides diverging towards the bottom.

WILLIAM G. WEHR.
